US00D944792S

(12) **United States Design Patent** (10) **Patent No.:** **US D944,792 S**
(45) **Date of Patent:** **** Mar. 1, 2022**

(54) **WEARABLE CONNECTED MODULE**

(71) Applicant: **Manufacture Modules Technologies SA**, Plan-les-Ouates (CH)

(72) Inventor: **Philippe Fraboulet**, Prévessin-Moëns (FR)

(**) Term: **15 Years**

(21) Appl. No.: **35/509,586**

(22) Filed: **Apr. 14, 2020**

(80) **Hague Agreement Data**

Int. Filing Date: **Apr. 14, 2020**

Int. Reg. No.: **DM/208521**

Int. Reg. Date: **Apr. 14, 2020**

Int. Reg. Pub. Date: **Jun. 12, 2020**

(51) **LOC (13) Cl.** **14-02**

(52) **U.S. Cl.**

USPC **D14/344**; D24/186

(58) **Field of Classification Search**

Primary Examiner — Darcey E Gottschalk

(57) **CLAIM**

The ornamental design for a wearable connected module, as shown and described.

DESCRIPTION

1. Wearable connected module

1.1 : Perspective

1.2 : Left

1.3 : Front

1.4 : Bottom

1.5 : Other perspective view with bracelet

1.6 : Other bottom view with bracelet

1.7 : Other perspective view with watch

The features of the wearable connection module shown in broken lines form no part of the claimed design.

1 Claim, 7 Drawing Sheets
